UNITED STATES PATENT OFFICE.

JOHN F. WILCOX, OF CLEVELAND, OHIO, ASSIGNOR TO RETORT COKE OVEN COMPANY, OF CLEVELAND, OHIO, A CORPORATION OF OHIO.

PROCESS OF MANUFACTURING COKE.

SPECIFICATION forming part of Letters Patent No. 725,904, dated April 21, 1903.

Application filed June 7, 1902. Serial No. 110,573. (No specimens.)

To all whom it may concern:

Be it known that I, JOHN F. WILCOX, a citizen of the United States, residing at Cleveland, in the county of Cuyahoga and State of Ohio, have invented or discovered new and useful Improvements in the Manufacture of Coke in Retort-Ovens, of which the following is a specification.

In the accompanying drawings, which make part of this specification, Figure 1 is a vertical section of a retort coke-oven, showing the same charged in the usual manner; Fig. 2, a similar section of the same, showing the coking completed; Fig. 3, a similar view showing the oven charged according to my invention previous to the withdrawal of the bottom and the partition; Fig. 4, a similar view showing the charge coked, and Fig. 5 a similar view showing the partition not extending to the bottom of the charge.

Many objections have been raised to the use of coke for metallurgical purposes made in retort or closed coke-ovens, the objections being based mainly on the presence of a greater or less amount of spongy porous friable coke. The pressure of this feature has been attributed to the insufficient coking of those portions of the charge in contact with the doors, or else to the portion in the top of the oven where the heat from the roof was insufficient to properly coke. As a matter of fact neither of the causes is responsible for the evil, except in a very minor degree, and I state below the true cause of the trouble, and I have invented a new and effectual method of remedying the evil and make possible the production of coke that has a uniform hardness and cell structures, the two prime requisites of a good metallurgical coke, and in addition an almost entire freedom from spongy or soft portions.

Heretofore it has been the general practice to charge the coal into retort-ovens in a solid mass, as shown in Fig. 1, either by laries or with a charging-machine from the front. During the distillation and coking process the heat is applied on the outside of the brick walls and transferred through the same to the coal. The heat being applied on both sides will coke the particles of coal next to both brick walls first, penetrating farther and

farther during the operation. As the center part of the coal charge will be the longest in a state of semipaste, this part will form the passage-way for most of the gases evolving from the coal, they naturally following the lines of least resistance. In actual practice the cake of coke when pushed from the oven will part in the middle and each piece of coke will have on its inner side at 3 a spongy porous feather-like end from one to two inches long, which is very friable and has not only little value, but in a heavily-burdened furnace is a positive detriment.

When coal, which swells greatly in the process of coking, is rammed into a retort-oven, so as to become solid between the walls thereof, or when a cake of such coal is rammed outside of the oven is of a size to entirely fill the same between its sides, the swelling of the coal exerts such a force as to distort the oven-walls.

The present invention refers to the charging of the retorts with charging-machines, where the coal is rammed into a solid block; but instead of having this rammed cake solid all through I divide the same and form an artificial space 3' for the passage of the gases instead of permitting the same to force a passage, thereby obviating the spongy ends and materially changing the texture of the inner ends of the coke and for the expansion of the coke if a coal swelling under heat is used.

Figs. 1, 2, 3, 4, and 5 represent cross-sections of a retort-oven, which may be about sixteen inches wide, six feet and a half high, and thirty-two to forty feet long. It is usually filled by dropping crushed coal through holes in the roof or else by inserting the coal en masse or in briquet form at one end of the oven. Fig. 1 represents an oven so charged. Fig. 2 shows the appearance of the stratification or lamination after coking. It will be noted that a well-defined fracture or fissure 3 extends from the bottom to the top of the mass, and as the charge is pushed the mass parts, and one half falls to the right and the other to the left. It will also be noted that the horizontal lines of cleavage all point upward and taper toward the center, indicating the line of passage of the gases during their expulsion. The walls of this fracture 3 contain

the greater portion of spongy coke. Fig. 3 shows a charge of coal similar to Fig. 1, with, however, a diaphragm or partition 4 inserted, which partition, together with the bottom 5, 5 is removed previous to firing, leaving an artificial channel or space vertically and longitudinally in the coal. The bottom 5 is a base on which the coal is rammed previous to its entrance in briquet form into the oven. After the briquet has been inserted the bottom 5 is withdrawn in the usual manner—for example, in the manner disclosed by the patent of Julius Quaglio, No. 365,489. Fig. 4 shows the said charge after coking. The 15 lamina-tion or cleavage is horizontal, and the inner surface of the masses of coke show the same cellular structure as the outer surfaces and are also practically free from the feathery fluffy friable portions that were a former accompaniment.

I make no claim as to the specific method of making the channel. In practice it is made three-fourths of an inch wide at the bottom and one and one-quarter inches at the top to 25 facilitate the withdrawal of the partition or core. The dividing partition or board can be withdrawn either endwise or, preferably, upward. In the latter case the partitions 4 would have to be withdrawn before the charges have 30 been entered into the ovens, because the roofs of the ovens are too close to the tops of the partitions to permit the withdrawal of the latter by an upward movement. When the partitions are withdrawn upward, the 35 charges must have channels before their transfer to the ovens. When the partitions are withdrawn endwise, they will preferably be withdrawn before entering the charges into the ovens, though they might be withdrawn 40 after their entrance into the ovens. In either

case the charges would be made outside the ovens and would before entrance into the ovens have portions spaced apart. In Fig. 5 the channel should preferably leave a thickness of coal at the bottom about the same 45 thickness as the mass on either side of the space 3'.

If desired, the charge of coal may have a plurality of spaces for the escape of gases.

Having described my invention, I claim— 50

1. The process of manufacturing coke in retort-ovens, consisting in forming the charges outside the ovens, entering into the ovens the charges so that a portion or portions of the same shall be spaced apart, and heating said 55 charge in said ovens.

2. The process of manufacturing coke in retort-ovens, consisting in forming the charges outside the ovens with a portion or portions of the same spaced apart, entering the charges 60 into the ovens, and heating them.

3. The process of manufacturing coke in retort-ovens, consisting in forming outside the ovens the charges with a portion or portions of the same spaced apart, the spaced portion 65 or portions extending from the top of the charges to a short distance from the bottom, entering the charges into the ovens, and heating the same.

4. As a step in the manufacture of coke, 70 the charging of retort coke-ovens with separate briquets spaced apart for the egress of the evolved gases.

Signed at Cleveland this 31st day of May, 1902.

JOHN F. WILCOX.
